UNITED STATES PATENT OFFICE

147,318

DESIGN FOR A SHOE

James M. Carpenter, Atlantic City, N. J.

Application April 17, 1947, Serial No. 138,445

Term of patent 7 years

(Cl. D7—7)

To all whom it may concern:

Be it known that I, James M. Carpenter, a citizen of the United States, residing at Atlantic City, in the county of Atlantic and State of New Jersey, have invented a new, original, and ornamental Design for a Shoe, of which the following is a specification, reference being had to the accompanying drawing, forming part thereof.

In the drawings,

Fig. 1 is a perspective view of a shoe showing my new design, the opposite side presenting substantially the same appearance as the side shown.

Fig. 2 is a rear view thereof.

I claim:

The ornamental design for a shoe, as shown and described.

JAMES M. CARPENTER.
